UNITED STATES PATENT OFFICE.

EDWIN H. STEEDMAN, OF ST. LOUIS, MISSOURI, ASSIGNEE TO CURTIS MANUFACTURING COMPANY, OF WELLSTON, MISSOURI, A CORPORATION OF MISSOURI.

VALVE STRUCTURE FOR COMPRESSORS.

Application filed February 6, 1928. Serial No. 252,301.

This invention relates to valve structures for compressors of the general type described in my pending application for patent Serial No. 206,010, filed July 15, 1927.

5 One object of my present invention is to provide a valve structure that embodies the essential features and distinguishing characteristics of the valve structure described in my said pending application for patent, but 10 which is equipped with an abutment member for the inlet valve of different construction and arrangement than the one shown in said application.

Another object is to provide a means of 15 different construction and arrangement for dislodging the abutment member for the discharge valve, the said abutment member being capable of being separated from the valve seat member and bodily removed from 20 the cylinder head without dislodging the valve seat member. Other objects and desirable features of my invention will be hereinafter pointed out.

Figure 1 of the drawings is a vertical 25 sectional view of a valve structure embodying my present invention.

Figure 2 is a horizontal sectional view, 30 taken on the line 2-2 of Figure 1, looking in the direction indicated by the arrows.

Figure 3 is a horizontal sectional view, 35 taken on the line 3-3 of Figure 1, looking in the direction indicated by the arrows.

Figure 4 is a vertical sectional view, illustrating another form of my present invention.

Figure 5 is a bottom plan view of the 40 abutment member for the discharge valve, taken on approximately the line 5-5 of Figure 4, looking upwardly.

Figure 6 is a top plan view of the valve 45 seat member, taken on approximately the line 6-6 of Figure 4, looking downwardly; and

Figure 7 is a horizontal sectional view, 50 taken on the line 7-7 of Figure 4, looking in the direction indicated by the arrows, with the inlet valve removed so as to more clearly illustrate the construction of the abutment member for said valve.

55 In Figure 1 of the drawings B designates the head of the cylinder of a compressor, 1 designates an intake passageway or chamber in said head which is herein illustrated as terminating in the bottom face of the head so that it will communicate with a suc-

tion passageway or intake passageway formed in the cylinder casting, and 2 designates a discharge passageway or chamber in the head B, which is herein illustrated as terminating in the bottom face of the head, 60 so that it will communicate with a discharge chamber or passageway in the cylinder casting. A valve structure that comprises an inlet valve, a discharge valve, a valve seat member and abutment members for the 65 valves, is removably mounted in a bore in the center of the cylinder head, said head being provided with a removable cap piece or cover plate 4 that is retained in operative position by any suitable means, as, for example, by fastening devices 5 that are 70 screwed into the head.

The valve structure just referred to is composed of a valve seat member C of annular form whose center opening 6 constitutes an 75 inlet port, said member C having an annular row of discharge ports 7 arranged in concentric relation with the inlet port 6, as shown in Figure 3. An inlet valve D, which consists of a flat disk, acts on a flat seat on 80 the underside of the valve seat member C, and a discharge valve E, which is of annular form, acts on valve seats on the top side of the valve seat member C. Valve abutment members F and G are arranged below and 85 above the valve seat member C, so as to limit the movement of the valves away from their seats.

The abutment member F for the inlet valve can either be formed integral with the 90 cylinder head B, or it can consist of a separate element pressed into a hole in the bottom face of the cylinder head or connected to said head in any other suitable way. Said abutment member F is provided with a disk-shaped solid central portion 8 whose upper side is constructed so as to serve as a pocket 95 8^a for the spring D' which holds the inlet valve seated, and at the periphery of the central portion 8 of said abutment member 100 are a plurality of radially-disposed arms 9 which are arranged in spaced relation, as shown in Figure 2, so that the spaces 10 between said arms will serve as an inlet passage for the air entering the cylinder, and a discharge passageway through which the medium compressed in the cylinder can escape into the discharge ports 7 in the valve seat member. The laterally-projecting arms 9 on the valve abutment mem- 110

ber F are provided with upwardly-projecting portions whose inner edges serve as lateral guides for the peripheral edge of the intake valve D, thereby holding said valve in operative relationship with its co-operating seat on the underside of the valve seat member C. The abutment member G for the discharge valve E is of annular form in general outline, and the center opening 11 of said member registers or aligns with the center opening 6 of the valve seat member C. Said abutment member G is provided on its underside with an annular flange 12 that bears on the top face of the valve seat member C at a point between the inlet port 6 and discharge ports 7 in the valve seat member so as to clamp the underside of the valve seat member C tightly against a shoulder 13 on the cylinder head. The bottom face 20 of that portion of the abutment member G which surrounds or projects laterally from the annular flange 12 on said member is spaced away from the top face of the valve seat member C, so as to provide for the vertical movement of the discharge valve E towards and away from its seat. The spring E' that holds the discharge valve seated is arranged in a pocket 14 on the underside of the abutment member G, as shown in Figure 1, and the cylindrical outer surface of the depending flange 12 on said member is used as a guide for the discharge valve E, thereby holding said valve in operative relationship with the ports 7. The springs that are associated with the inlet valve and discharge valve can be of any preferred type, but they are herein illustrated as consisting of coiled expansion springs, the spring D' for the inlet valve being of the spiral type.

40 The valve structure above described is retained in operative position in the cylinder head by retaining device which consists of a nut H screwed into threads 15 on the side wall of the bore in the cylinder head and provided at its lower end with an annular portion 16 that acts on packing 17 which is positioned in an annular space between the abutment member G and the side wall of the bore in the cylinder head. As shown 50 in Figure 1, the abutment member G has an inclined surface 18 that forms the bottom of the annular space in which the packing 17 is positioned. When the nut H is screwed downwardly, the packing 17 is compressed and forced tightly against the walls of the space in which it is arranged, and the abutment member G is forced downwardly against the valve seat member C, thereby causing said valve seat member to be clamped tightly against the shoulder 13 provided for same on the cylinder head. This produces an air-tight joint between the upper surface of the valve seat member C and the annular flange 12 on the abutment member G, and it also produces a gas-tight joint

between the cylinder head and abutment member G. In order that the abutment member G may be dislodged and removed easily from the cylinder head, said member is provided at its upper end with a laterally-projecting flange 19 that laps over a portion of the nut H, so that when said nut H is backed off or screwed upwardly out of the head, it will engage the flange 19 and exert an upward thrust on the abutment member G, thereby causing said member to be dislodged or disengaged from the valve seat member C. After the abutment member G has been withdrawn from the bore in the cylinder head, the valve seat member C can be removed from said bore. The laterally-projecting flange 19 at the upper end of the abutment member G can be formed conveniently by a flanged nut that is connected with said abutment member by a screw 85 thread of opposite hand from the thread on the nut H that is screwed into the thread 15 on the cylinder head. In order that the valve seat member C will automatically locate itself in the cylinder head when said member is being installed, the head is provided with a plurality of vertically-disposed, spaced guides 2^a against which the peripheral edge of said valve seat member bears when it is being installed.

95 A valve structure of the kind above described has few parts; it is inexpensive to manufacture and easy to maintain in an operative condition; it can be installed or removed easily from the cylinder head without breaking any pipe connections; it is of such design that valves of large area can be easily installed in a cylinder of relatively small diameter; it is of such design that the valves have maximum effective openings 105 with minimum clearance; and it is an improvement on the valve structure shown in my said pending application for patent, in that there is less tendency for the abutment member for the inlet valve to warp and the valve seat member has one less joint that is liable to leak, due to the fact that said abutment member is permanently mounted in the cylinder head and is separable from the valve seat member instead of being 110 clamped to the valve seat member by a bolt that passes through the center of the same.

115 In Figures 4, 5, 6 and 7 of the drawings I have illustrated another form of my invention, wherein the parts which are the same as the parts of the structure shown in Figure 1 are designated by corresponding reference characters. The structure shown in Figure 4, however, is provided with an annular inlet valve D¹⁰, and both the inlet valve and the discharge valve are so arranged that the air or other medium operated on by the compressor can flow over the inner and outer edges of both valves. Thus, as 120 shown in Figure 4, the inner edge of the

125 130

discharge valve E is held spaced away from the annular flange 12 on the abutment member G by a plurality of vertically-disposed ribs 20 on the outer side of said flange that 5 are arranged in spaced relation and which serve as guides for the inner edge of said valve. The ribs 20 merge into horizontally-disposed ribs 21 on the underside of the abutment member G that serve as stops for 10 the discharge valve, and which insure said valve assuming such a position when it is wide open that the air or medium escaping from the cylinder can pass upwardly over the inner edge of the discharge valve, and 15 thence laterally over the top face of said valve.

Similarly, the air or other medium that is drawn into the cylinder of the compressor flows over the inner and outer edges of 20 the annular inlet valve D¹⁰. In order to attain this result it is necessary to use a valve seat member and an abutment member for the inlet valve which are of slightly different construction from those used in the 25 form of my invention illustrated in Figure 1. Thus, the valve seat member C¹⁰, shown in Figure 4, is provided with a solid central portion 22 of greater diameter than the diameter of the center opening in the inlet 30 valve D¹⁰, and said valve seat member is also provided with a plurality of inlet passageways 6^a which are located between the solid central portion 22, and the annular portion of said member in which the discharge ports 7 are formed. The abutment member F¹⁰ for the inlet valve is also provided with a center opening 10^a, as shown in 35 Figure 7, which constitutes an inlet opening in addition to the openings 10 between the arms 9 on said abutment member which 40 guide the inlet valve during its movement towards and away from its seat.

Having thus described my invention, what I claim as new and desire to secure by Letters Patent is:

1. In a compressor, the combination of a cylinder head provided with a bore, a removable valve structure in said head comprising a substantially disk-shaped valve seat member arranged adjacent the inner end of the bore in engagement with a supporting surface on the head, valves which act on seats on the top and bottom faces of said valve seat member for controlling inlet and outlet ports in said member, an abutment member for the bottom valve, separable from the valve seat member and permanently mounted in the head below the valve seat member, a separate abutment 50 member for the top valve removably mounted in said bore above the valve seat member, and a retaining device detachably connected to the head and arranged to coact with a packing to produce a tight joint 55 between the head and the top abutment member and also cause the valve seat member to be clamped tightly against the supporting surface on the head.
2. In a compressor, the combination of a cylinder head provided with a bore, a removable valve structure in said head comprising a substantially disk-shaped valve seat member arranged adjacent the inner end of the bore in engagement with a supporting surface on the head, valves which 70 act on seats on the top and bottom faces of said valve seat member for controlling inlet and outlet ports in said member, an abutment member for the bottom valve, separable from the valve seat member and permanently mounted in the head below said valve seat member, a separate abutment member for the top valve removably mounted in said bore above the valve seat member, a packing that co-acts with the head and the top abutment member, a retaining device detachably connected to the head and arranged to expand said packing 75 and exert pressure on the top abutment member in a direction to cause it to clamp the valve seat member tightly against the supporting surface on the head, springs for the valves arranged in pockets in the abutment members, and guides on said abutment members for the valves.
3. In a compressor, the combination of a cylinder head provided with a bore, a removable valve structure in said head comprising a substantially disk-shaped valve seat member arranged adjacent the inner end of the bore in engagement with a supporting surface on the head, valves which act on seats on the top and bottom faces of said valve seat member for controlling inlet and outlet ports in said member, an abutment 90 member for the bottom valve permanently mounted in the head and having no direct connection with the valve seat member, a separate abutment member for the top valve removably mounted in said bore above the valve seat member, a retaining device detachably connected to the head and arranged to exert pressure on the top abutment member in a direction to cause it to clamp the valve seat member tightly against the supporting surface on the head, packing between the top abutment member and the cylinder head arranged so as to be forced tightly against said parts by the retaining device, and a lateral projection on the top abutment 95 member arranged so that said retaining device will engage the same, and thus dislodge said top abutment member when the retaining device is removed from the head.
4. In a compressor, the combination of a cylinder head provided with a bore, a removable valve structure in said head comprising a substantially disk-shaped valve seat member arranged adjacent the inner end of said bore in engagement with a supporting sur- 100

face on the head, valves that act on seats on the top and bottom faces of said valve seat member and control inlet and outlet ports in said member, a bottom valve abutment member permanently mounted in the head below the valve seat member and provided with a plurality of spaced, upwardly-projecting guides that co-operate with the peripheral edge of the bottom valve, said abutment member having openings or passageways in same, a top valve abutment member arranged above the valve seat member, a retaining device for the valve structure detachably connected to the head, and packing arranged between the head and the top abutment member that is adapted to be forced tightly against said parts by the retaining device.

5. In a compressor, the combination of a cylinder head provided with a bore, a removable valve structure in said head comprising a substantially disk-shaped valve seat member arranged adjacent the inner end of said bore in engagement with a supporting surface on the head, valves that act on seats on the top and bottom faces of said valve seat member and control inlet and outlet ports in said member, a bottom valve abutment member permanently mounted in the head below the valve seat member and separable from the valve seat member in the operation of removing the valve structure, a plurality of spaced, upwardly-projecting guides on said abutment member that co-operate with the peripheral edge of the bottom valve, said abutment member having openings or passageways in same, a top valve abutment member arranged above the valve seat member, a retaining device for the valve structure screwed into the head and provided with a portion that is adapted to act upon a packing interposed between the head and the top abutment member and force the packing tightly against said parts, and a part screwed into the top abutment member and adapted to co-operate with the retaining device to dislodge the top abutment member during the operation of removing the retaining device from the head.

6. In a compressor, the combination of a cylinder head provided with a bore, a removable valve structure in said head comprising a substantially flat valve seat member arranged in said bore in engagement with a shoulder on the head and provided with inlet and discharge openings, a disk-shaped inlet valve that acts on a seat on the underside of the valve seat member, an annular discharge valve that acts on the seat on the top face of said valve seat member, springs for holding said valves seated, an abutment member for the inlet valve permanently mounted in and carried by the head, an abutment member for the discharge valve removably mounted in said bore, and a means for forming a tight joint between the head and the top abutment member and for causing said top abutment member to hold the valve seat member tightly against the shoulder provided for same on the cylinder head.

7. In a compressor, the combination of a cylinder head provided with a bore, a removable valve structure in said head comprising a substantially disk-shaped valve seat member arranged adjacent the inner end of said bore in engagement with a shoulder on the head, an annular inlet valve that acts on a seat on the underside of the valve seat member, an annular discharge valve that acts on a seat on the top face of said valve seat member, springs for said valves, an abutment member for the inlet valve permanently mounted in the head, an abutment member for the discharge valve removably mounted in said bore, pockets in the abutment members for the valve springs, and a means for forming a tight joint between the head and the top abutment member and for causing said top abutment member to bear tightly against the valve seat member and hold the same tightly against the said shoulder on the cylinder head, said abutment members having guides for the valves arranged so that the medium drawn into or discharged from the cylinder of the compressor can flow over the inner and outer edges of the valves.

EDWIN H. STEEDMAN.
